UNITED STATES PATENT OFFICE.

ALBERT DELAS, OF PARIS, FRANCE, ASSIGNOR TO DELAS CONDENSER CORPORATION, OF NEW YORK, N. Y., A CORPORATION OF DELAWARE.

STEAM EJECTOR WITH COOLED DIFFUSER.

Application filed October 19, 1920, Serial No. 417,989. Renewed August 4, 1924.

To all whom it may concern:

Be it known that I, ALBERT DELAS, a citizen of the Republic of France, residing at Paris, France, have invented certain new and useful Improvements in Steam Ejectors with Cooled Diffusers, of which the following is a full, clear, and exact description.

The invention which constitutes the subject matter of this application relates to ejectors, and has for its object to effect certain improvements in the construction and method of operation of ejectors of the type disclosed in my Patents No. 1,374,990, April 19, 1921, and Nos. 1,499,349 and 1,499,350, July 1, 1924, and my copending application Ser. No. 260,601½, filed Oct. 31, 1918.

In my above mentioned prior applications I have pointed out certain novel important results obtained by circulating cooling fluid around the walls of the converging portion of the diffuser and further advantages and important results obtained by also cooling the neck and outlet portions of the diffuser. Stated somewhat generally, such cooling increases both the efficiency and stability of operation of ejectors. A preferred form of such ejector comprises a diffuser provided with a converging inlet portion, a substantially cylindrical neck portion, a substantially cylindrical outlet portion and with means for circulating a cooling fluid around the exterior of the walls of the said inlet, neck and outlet portions of the diffuser.

In order to enhance the cooling effect, the walls of the diffuser should be made thin and out of good heat conductivity. During the operation, the diffuser is subjected to wide fluctuations of temperature, especially when steam is passing through the diffuser, and, through accident or mistake, the circulation of the cooling fluid is stopped. Under such circumstances the diffuser may reach a temperature higher than that of its enclosing casing, and in the absence of special provisions would be subjected to strains and consequent buckling or other deformation. In my prior applications I have disclosed arrangements in which the diffuser is provided with an expansion joint at, at least, one end thereof to permit expansion and contraction of the diffuser with respect to the remaining structures. If sea water is to

be employed as the cooling fluid it is important that the expansion-permitting-means be so tight that entrance thereof into the diffuser or path of the motive and entrained fluid is prevented, especially when the latter mixture is to be condensed and the fluid of condensation eventually returned to the boilers.

One of the objects of the present invention is to provide expansion-permitting-means meeting the above stated requirements without sacrificing the solidarity and simplicity of the general structure.

In my said prior applications I have disclosed arrangements in which the diffusers are surrounded by sleeves in comparatively close proximity to the same and between which diffusers and sleeves the cooling fluid is caused to flow. By virtue of this arrangement a maximum cooling effect is obtained for a given quantity of cooling fluid. I have discovered that it is especially important that the wall of the neck of the two diffusers should be maintained at a low temperature.

Another object of the invention is to provide an arrangement and method for intensively cooling the diffuser neck portion.

A further object of the invention is to provide a reservoir or storage chamber for the cooling fluid adjacent and surrounding the diffuser so that in case of cessation of circulation of said fluid the otherwise incidental rise in temperature of the diffuser walls is prevented. Other objects and advantages will appear as the invention is hereinafter disclosed.

Referring to the drawings which illustrate what I now consider preferred forms of apparatus embodying my invention:

Fig. 1 is a sectional elevation of a single stage ejector embodying certain features of the invention.

Fig. 2 is a view similar to Fig. 1, but illustrating an additional feature of invention.

Figs. 3 and 4 are views similar to Fig. 2, but illustrating modifications.

Fig. 5 is a sectional elevation of a two stage ejector system embodying certain features of the invention.

Fig. 6 is a sectional elevation of a two

stage ejector system in which the two ejectors are arranged side by side instead of in axial alignment, as in Fig. 5.

Fig. 7 is a section taken on the line A—B of Fig. 6.

Fig. 8 is a view similar to Fig. 6, but illustrating certain modifications.

Fig. 9 is a view similar to Fig. 8, but illustrating further modifications.

Fig. 10 is a section on the line A'—B' of Fig. 9.

Figs. 11 and 12 are enlarged detail views illustrating certain features of the various forms of the invention.

Referring to Fig. 1, it will be seen that the ejector there illustrated comprises an enclosing casing 1 provided with a nozzle 2 adapted to be supplied with steam or other elastic motive fluid under pressure and to discharge the same into the chamber 3. The latter is adapted to communicate at 4 with the source of fluid, such as air, vapor, steam or mixture of the same, whose pressure is to be raised in the ejector. Suitably secured within the casing 1 is a tubular diffuser 5 through which the mixture of motive fluid and entrained fluid passes. I have illustrated my preferred form of diffuser, which comprises a converging inlet portion 6, a substantially cylindrical neck portion 7 and a substantially cylindrical outlet portion 8. Water or other cooling fluid is introduced through the opening 9 into the annular chamber 10, bounded by the casing 1 and a cylindrical portion 11 of a sleeve member 12 suitably secured within the casing and surrounding the upper end of the diffuser 5. The member 12 terminates at its lower portion in a tube which, speaking generally, conforms to the shape of the exterior of the diffuser. It will be noted that the member 12 is constricted near the neck of the diffuser. The cylindrical portion 11 is provided with a peripheral row or series of holes 13 through which the cooling fluid flows from the annular chamber 10 into the space between the sleeve 12 and the exterior of the diffuser 5. The sleeve 12 discharges into a reservoir or storage chamber 14 provided in the casing 1 and surrounding the sleeve and diffuser. The cooling fluid leaves the chamber 14 through the hole or aperture 15 provided in the casing 1 adjacent the top of the chamber 14.

It will be understood by those skilled in the art that steam issuing from the nozzle 2 will entrain the air and vapor or other fluid in the chamber 3 and impart velocity thereto. The mixture of motive and entrained fluids then passes through the diffuser 5 when, by conversion of velocity into pressure, its pressure is raised. Water or other cooling fluid is supplied from any suitable source and flows as follows: Entering at the aperture 9 the cooling fluid flows

around the chamber 10 and through the holes 13 into the space between sleeve 12 and diffuser 5. It will be appreciated that the cooling fluid is spread evenly around the diffuser by virtue of the construction above described. The cooling fluid then flows downwardly in the sleeve 12 and around the exterior of the walls of the diffuser 5 cooling the same. The device is thereby rendered highly stable and efficient in its operation. The cooling fluid flows from the sleeve 12 into the chamber 14 and out at exit 15. Even though the circulation should cease for any reason during the operation of the ejector the diffuser walls would nevertheless be maintained at a comparatively low temperature by the large mass of fluid in the storage chamber 14.

As previously stated, it is important that the neck of the diffuser be maintained at a low temperature. By virtue of the constriction of the sleeve 12 the velocity of the stream of cooling fluid is raised at and adjacent the constricted section so that the wall of the neck portion of the diffuser is intensively cooled.

For reasons hereinbefore stated, I prefer to provide the diffuser 5 with expansion-permitting-means which may assume various forms. One form is illustrated in Fig. 2 and may be constructed substantially as follows:

The diffuser 5 is fixedly secured at its upper end with respect to the casing 1, but its outlet end 8 passes through a stuffing-box 16. The latter comprises a gland portion secured to the casing 1 and in which the packing is held by a nut or locking ring 17. Obviously a fluid-tight, diffuser-expansion-permitting joint is provided by the structure described, and intermingling of the cooling fluid and ejected fluid is prevented.

A different form of expansion joint is illustrated in Figs. 3 and 11 and may be constructed substantially as follows: The lower end 8 of the diffuser 5 has secured thereto an externally threaded annular member or screw 18 provided with a nut 19. A centrally apertured undulated or corrugated disc or diaphragm 20 of metal or other suitable material is secured between the members 18 and 19. The outer edge of the said disc 20 is secured between the casing 1 and a nut 21 cooperating therewith as clearly indicated in Fig. 11. A fluid-tight but diffuser-expansion-permitting joint between the diffuser and casing 1 is thereby secured.

In both of the forms of invention illustrated in Figs. 2 and 3 the diffuser is placed in position by inserting the same downwardly into the casing 1 and subsequently, in the form shown in Fig. 2, tightening the nut 17 of the stuffing box or, in the case of the form shown in Figs. 3 and 11, tightening the nut 19. The nuts 19 and 21 may

be provided with notches 22 to effect their rotation. I prefer also to provide the lower extremity of the diffuser and member 18 with notches 23, one of which is shown in Fig. 11, whereby the diffuser and member 18 may be held against rotation while the nut 19 is being turned, thereby preventing any torsional strains either on the diffuser or the joint between the same and said member 18.

In the form of invention shown in Figs. 4 and 12 the lower end of the diffuser is fixed and the upper end permitted to move with respect to the casing. The lower end 8 of the diffuser has secured thereto an externally threaded member 24 adapted to screw into the casing 1 thus constituting a fixed joint. The upper part of the diffuser is provided with an undulated or corrugated portion 27, whereby the diffuser may be elastically or yieldingly connected to the casing. The member 24 may be provided with notches 28 for turning the same. In order to prevent torsional strain between the diffuser and member 24 during the turning of the latter notches 29 are preferably provided in the lower end of the diffuser. By inserting the wrench or other tool in both notches 28 and 29 the diffuser and member 24 will turn as a unit and all tendency toward relative rotation of these members is avoided.

I have described above some of the preferred forms of fluid-tight expansion joints which may be employed and have thus far described certain features of the invention as applied to single stage ejectors. The invention may also be applied to multi-stage ejectors, as will hereinafter appear.

In Fig. 5 I have shown a two stage ejector in which the two ejectors are axially arranged and connected in series to act on the elastic fluid whose pressure is to be raised. In view of the similarity between the two ejectors and the one shown in Fig. 1 no detailed description is necessary. Suffice it to say that the second stage ejector has certain of its parts, which correspond to the parts of the first stage ejector, designated by the same reference numerals with an added prime. In this form of the invention the water or other cooling fluid enters at 9, leaves the first stage at 15, passes through the pipe 30 into the second stage at 9' and leaves at 15'. It will be noted that the water passes around the first stage diffuser first rather than through the second stage first because water as cold as possible should be employed in the first stage where the pressure is lowest.

While the arrangement of ejectors shown in Fig. 5 possesses many desirable features, it is disadvantageous to a certain extent, in that the steam or motive fluid nozzle 2', of the second stage ejector, and a portion of its supply pipe are located directly in the

path of the mixture of motive and entrained fluid discharged from the first stage and entrained in the second stage, giving rise to an objectional elevation in temperature of the last mentioned fluid. An arrangement 70 for overcoming this objection is illustrated in Figs. 6 and 7 of which many of the illustrated parts will be recognized in view of the preceding description.

In Figs. 6 and 7 the ejectors of the two 75 stages are placed side by side, the first stage ejector discharging its mixture of motive and entrained fluids into the second stage chamber 3' through a pipe 31. While the water or other diffuser-cooling fluid may be 80 passed through the two stages successively, as shown in Fig. 5, it is possible, and in some respects preferable, to pass this cooling fluid through the two stages in parallel. In this arrangement the water entering the 85 cooling spaces of both stages is cold, as that entering the second stage has not been heated by first passing through the first stage. The surface of both diffusers is maintained as cold as possible which is highly advantageous. One arrangement whereby the last described circulation of the cooling fluid may be secured is shown in Figs. 6 and 7, and may be described as follows:

The water or cooling fluid is introduced at 95 9, and spreads in the annular chamber 10 of the first stage ejector where it divides. A portion flows through the first stage between the sleeve 12 and diffuser 5 while another portion flows through the channel 32 into 100 the annular chamber 10' of the second stage. The passage of the cooling fluid through each stage will be understood in view of the preceding description. The cooling fluid discharged from the first stage at 15 passes 105 through a channel or passage 33 into the storage space 14' of the second stage which discharges through the exit opening 15'.

In multi-stage ejector systems it is quite often desirable to employ an interstage jet 110 condenser. When the water employed for cooling is pure (not salt water), or when the fluid discharged from the ejectors is not to be returned to boilers, the water supplied to interstage condensers may be tapped from 115 the water of the diffuser-cooling system. A suitable arrangement whereby this may be accomplished is illustrated in Fig. 8, and may be constructed substantially as follows:

Calling attention to the last mentioned 120 figure, it will be seen that the outlet 8 of the first stage diffuser 5 has attached thereto a bell 34 provided with holes or perforations 35 through which a part of the cooling fluid in the chamber 14 enters to condense the 125 steam or other condensable fluid discharged from the first stage. The condensed fluid is withdrawn or leaves at 36 while the gaseous or elastic fluid passes to the second stage through the channel or passage 38 130

in the direction of the arrow 37. In this form of the invention it is not necessary that there be perfect tightness in the yielding joint between the bell 34 and the outlet portion 8 of the diffuser 5, but the joint need only be properly fitted.

In certain cases, for example when the multi-stage ejectors are to be employed in connection with a turbine system embodying 10 main condensers of the surface type and when the fluid discharged from the ejectors is to be employed to augment and heat the boiler feed water, the form of invention illustrated in Fig. 8 is not desirable, as the 15 cooling fluid is impure. The form of invention shown in Figs. 9 and 10 may then be employed.

In this form of the invention the bell 34 is connected to the outlet 8 of the diffuser 5 by a fluid tight joint and the upper part of 20 said bell is located in a chamber 39 adapted to be supplied at 40 with water or condensing fluid from any suitable source, such as a main condenser (not shown). In certain 25 cases the water from the main condenser, a part of which is injected into the inter-stage condenser to condense the steam issuing from the first stage, is too warm to be employed for cooling the diffuser and should 30 be separated from the cooling fluid. By virtue of the structure shown in Figs. 9 and 10 this result is also achieved.

In accordance with the provisions of the 35 patent statutes, I have herein described the principle of operation of my invention, together with the apparatus which I now consider to represent the best embodiments thereof, but I desire to have it understood that the apparatus disclosed is only illustrative and the invention can be carried out by other means. Also, while it is designed 40 to use the various features and elements in the combinations and relations described, some of these may be altered and others 45 omitted, and some of the features of each modification may be embodied in the other

without interfering with the more general results and effects outlined, and the invention extends to such use.

What I claim is:

1. The method of cooling the diffuser of an ejector which comprises causing a flow of fluid in contact with the exterior of the diffuser, and increasing the velocity of the fluid adjacent the neck of the diffuser. 50

2. The method of cooling the diffuser of a steam actuated ejector which comprises causing a flow of liquid in contact with the exterior of the diffuser, and increasing the velocity of the liquid adjacent the neck of the diffuser. 55

3. An ejector comprising, in combination, a nozzle, a chamber having an inlet for the fluid to be entrained and into which said nozzle discharges, a diffuser communicating with said chamber, means for causing a flow of liquid in contact with the exterior of said diffuser, and means whereby the velocity of the fluid stream is increased adjacent the neck portion of said diffuser. 60

4. An ejector comprising, in combination, a nozzle, a chamber having an inlet for the fluid to be entrained and into which said nozzle discharges, a diffuser communicating with said chamber, and means comprising a converging-diverging sleeve surrounding said diffuser for causing a flow of cooling fluid in contact with the exterior of said diffuser. 70

5. An ejector comprising, in combination, a diffuser, a casing surrounding said diffuser and forming a cooling chamber around the same and substantially sealed at its lower portion, and means whereby a cooling liquid may be circulated through said chamber, 75 said means comprising an inlet for the fluid and an outlet located adjacent the upper end of said diffuser. 80

In testimony whereof I hereto affix my signature.

ALBERT DELAS.
